UNITED STATES PATENT OFFICE.

MASAMICHI IGARASHI, OF TOKYO, JAPAN.

RAILWAY-SLEEPER.

1,366,385.

Specification of Letters Patent. Patented Jan. 25, 1921.

Application filed November 29, 1919. Serial No. 341,369.

To all whom it may concern:

Be it known that I, MASAMICHI IGARASHI, a subject of the Emperor of Japan, residing at No. 93 Susakicho, Mukojima, Honjoku, the city of Tokyo, the Empire of Japan, have invented certain new and useful Improvements in Railway-Sleepers, entitled M. I. Railway Sleeper, of which the following is a specification.

10 This invention relates to railway sleepers or ties of the kind having the rail supports lodged in pockets or recesses in the sleeper.

The primary object of the present invention is to enable the rail supports to be more 15 easily and cheaply removed and renewed than heretofore in sleepers of this kind.

This object is achieved by means of holding down members for the rail supports which traverse side walls of the pocket 20 through holes in said walls, and fillings in said holes for fixing the holding down members.

The invention is more particularly intended 25 for use in concrete and similar sleepers.

In order that said invention may be clearly understood and readily carried into effect, the same is described more fully with 30 reference to the accompanying drawings, in which:—

30 Figure 1 is a longitudinal section of a railway sleeper in accordance with this invention, showing a rail fixed, by means of spikes, to a rail support consisting of a block of wood or like material firmly embedded in the pocket or recess in the sleeper, which is of reinforced concrete.

Fig. 2 is a plan showing the block embedded in the sleeper.

Fig. 3 is a cross section thereof.

40 In all figures, the same symbol represents a similar part.

Referring to the drawings, a pocket or recess is formed in the sleeper A made of reinforced concrete, and a wooden block B is 45 inserted in the recess, which has spike holes C as shown in Fig. 2 provided in its three side-walls, a water discharge hole O being made in the bottom of said recess, and a space or clearance d being provided around 50 the block B, which space is filled with coal tar or asphalt and hemp, by means of which the block B is maintained in its proper position, while, at the same time, it serves the purpose of preventing rain or other water 55 coming in at the inner side. After thus

setting the block spikes S are driven through the holes C into the block in such a manner that the heads of the spikes S slightly project on the outside of the side-walls of the recess, and the spaces in the spike holes C 60 are filled with cement mortar to fix the spikes in position.

When the block B is to be replaced, the cement mortar in the spike holes C is broken or crushed, whereby the spikes S can be 65 withdrawn from said holes, which allows the block to be easily replaced without damage to the sleeper member; the rail l may be fixed to the block either before or after the latter is secured to the sleeper member A.

Having now particularly described and ascertained the nature of said invention and in what manner the same is to be performed, I declare that what I claim is:

1. In a railway tie having pockets therein at the rail crossings, rail supports in the pockets, holding down members for the supports, said members traversing side walls of the pockets through holes in the walls, and 80 fillings in said holes for fixing the holding down members.

2. In a railway tie of concrete having pockets therein at the rail crossings, wooden blocks in the pockets adapted to support the rails, members traversing side walls of the pockets through holes in the walls, and cement fillings in said holes for fixing the holding down members.

3. In a railway tie of concrete having 90 pockets therein at the rail crossings, wooden blocks in the pockets adapted to support the rails, spikes traversing three side walls of the pockets through holes in the walls and entering the block laterally, and cement fillings adapted to secure the spikes in position.

4. In a railway tie having pockets therein at the rail crossings, rail supports in the pockets, holding down members for the supports, said members traversing side walls of the pockets through holes in the walls, and 100 easily renewable fillings in said holes for fixing the holding down members.

In testimony whereof, I affix my signature in presence of two witnesses.

MASAMICHI IGARASHI.

Witnesses:

ROGER P. STONE,
S. HORIJE.
